UNITED STATES PATENT OFFICE.

J. THEODORE GURNEY, OF BOSTON, MASSACHUSETTS.

TWO-WHEELED VEHICLE.

SPECIFICATION forming part of Letters Patent No. 361,941, dated April 26, 1887.

Application filed September 23, 1882. Renewed June 28, 1886. Serial No. 206,534. (No model.)

To all whom it may concern:

Be it known that I, J. THEODORE GURNEY, a citizen of the United States, residing at Boston, in the county of Suffolk and State of Massachusetts, have invented certain new and useful Improvements in Carriages, of which the following is a specification, reference being had therein to the accompanying drawings.

Figure 1 is a side elevation of a two-wheeled vehicle embodying my improvements. Fig. 2 is a rear elevation of the same. Fig. 3 is a front view of a cab with non-adjustable shafts. Fig. 4 is a transverse vertical section through the body of the vehicle on the line $y-y$, Fig. 1. Fig. 5 is a perspective of the frame-work of the vehicle detached. Fig. 6 is a perspective of the running-gear detached. Fig. 7 is a top plan view of the shafts. Fig. 8 is a section across the shaft on the line $x-x$, Fig. 1. Fig. 9 is a top plan view of the seats. Fig. 10 shows a flexible connection between the shafts and the body, made by means of a pivot or hinge. Fig. 11 shows the removable blinds combined with an ordinary top. Fig. 12 shows one of the removable blinds, a part being broken away.

In the drawings, A A represent the supporting-wheels mounted on a cranked axle having wrists formed of the wheel-arms a and the parts a' , the wrists being connected by the cranked portion a' .

B B are side springs secured to the axle, preferably to the wrist parts a . The body rests upon these springs, being connected thereto by intervening parts, such as hangers B^3 at the front and a cross-spring support, B' , at the rear.

The body is formed with a frame-work provided with panels inclosing the front and sides of the box or lower part of the body. To adapt the body to be uncovered, I construct the frame-work of the box of parts which do not extend above the side paneling. The box-paneling is formed with uprights $K K'$, bottom connecting-bars, K^2 , and sills K^3 , these being so shaped and arranged as to form a box with a wider portion to receive the seats and a narrower portion at the bottom.

I I represent the side panels of the wider part of the box by the sides of the wheels.

I^1 is the front panel, $I^2 I^3$ the rear panels,

and $I' I'$ converging side panels at the lower part of the box. These may be of any suitable material, though I prefer to employ sheet metal, as is fully described and shown in another application, Serial No. 132,922, pending herewith.

The passengers' seats are situated transversely to the axle, as shown in Figs. 4 and 9, and they may be of any of the forms now well known, though I prefer to have each made with a broader portion, Q, and with a narrower, q, for the convenience of passengers.

M M represent the doors for closing the rear entrance, being hinged at m . They extend from the step up to the top of the box, and are so arranged that a tasteful appearance shall be preserved when the box is uncovered.

The top part of the cab can be either made rigid with the box part, as in Fig. 1 and others, or can be so constructed and arranged that the box can, as aforesaid, be uncovered in pleasant weather. The cover-frame has supporting-bars $L L' N$ and top cross-bars, L^2 . When it is intended to have the box of the vehicle adapted to be uncovered, the frame is provided with dowels i (see Fig. 4) and set-screws or other suitable devices for fastening it in position. (Not shown.)

In Fig. 5 the cover-frame has, for supporting the roof, inwardly-converging ribs L^5 , united by a central supporting-piece, L^4 ; but the roof part can be of the ordinary style, if desired, as shown in Fig. 11.

With the cabs I combine removable blinds or eaves. They are indicated generally by R R, each being preferably made in two sections, each section having a side part, r' , a front part, r^2 , and a rear part, r^3 . $r r$ are brackets for detachably securing them to the cover-frame, they being adapted to be fastened by screws and pins, the latter, as shown, extending up into apertures in the cross-pieces L^2 . These blinds or eaves may be made of any suitable material—as, for instance, blind-slats, overlapping each other, or of thin boards—and they may be applied to cab-tops of the ordinary style, as shown in Fig. 11.

$R^2 R^2$ represent flexible curtains or covers at the sides of the cover-frame, which can be used to protect the passenger-box. They are shown as supported on rollers, and are pre-

ferably mounted on the blinds R; but covers or curtains can be otherwise mounted and used for the same purpose. To more tightly inclose the box the top is adapted to carry sashes or 5 panels, the cover-frame being constructed to receive the sashes or panels in rabbits.

C C represent the shafts. They are flexibly and adjustably connected with the vehicle; but I do not herein claim any of the features 10 incident to this part of the structure, reserving the right to claim the same in other applications pending herewith, they being Serial Nos. 132,922 and 132,923. The shafts are joined by a cross-bar, F⁵, having a whiffletree, F⁶, and a 15 loop or clevis, f⁵. The latter is connected to the driver's support by a strap, f⁸, running from an eye at f⁶ to an eye, F⁷, to prevent too great play of the body or shafts.

H' H' are the steps, and H² H³ H⁴ the 20 supports thereof bolted to the shafts.

F is a spring connected to the shafts and interposed between them and the vehicle. The shafts are adjusted by screw-rods F², carrying cranks F³, the rods being in bearings G G' and 25 engaging with eyes F', connected with the said spring F. In addition to these parts the shafts are provided with flexible connecting devices, either a spring, as at E, or hinges, as at E'. The hinges may be made in any suitable way, 30 that shown having ears e' and a pivot-bolt for the shaft. The springs E are secured by the part e², inserted into the cab-body and secured to the frame. The hinges may be fastened by parts similar to those at e', or in any of the 35 now well-known ways. In either case the shaft-connections are arranged in or near the horizontal planes of the passengers' seats—that is to say, in the horizontal planes of the greatest weight in the interior when the cab is loaded— 40 in order to apply the draft to the best advantage.

O represents a signal-bell with a rod, O', and handle O².

K' is a board back of the driver, carrying, if desired, a mirror, O⁴.

The driver's support comprises the seat D⁶ and the foot-rest D⁵, supported on the metallic brackets D D' D² D³, extending out from the body to carry said parts; but these need not be herein described in detail, they being fully described in another application, Serial No. 132,923, pending herewith; nor do I herein claim any of the combinations set forth in the claims in either of the aforesaid other applications Serial Nos. 132,922 and 132,923, nor the 55 combinations claimed in my application Serial No. 57,054, on which patent No. 272,238 has been granted to me, limiting this case to the claims set forth below.

What I claim is—

1. In a cab, the combination, with the frame which supports the roof or cover, of removable laterally-extending blinds or eaves, substantially as and for the purposes set forth.

2. In a cab, the combination, with the upright bars at the sides, of the roof-supporting ribs extending upward and inward and joined at the center by a support independent of each of the ribs, substantially as set forth.

3. In a two-wheeled cab, the combination of 70 the body having a rear doorway, the seats transverse to the axle, the closed side and front panels, the interior box-frame terminating at or near the tops of the side panels, and a cover detachably supported upon the body-frame, 75 substantially as set forth.

In testimony whereof I affix my signature in presence of two witnesses.

J. THEODORE GURNEY.

Witnesses:

HENRY H. PAGE,
CHARLES W. GAULT.
